INTERLOCKING ROOFING TILE

Richard Hedrich, Sr., Los Angeles, Calif., assignor
of one-half to Albert P. Myers, Los Angeles,
Calif.

Application March 31, 1939, Serial No. 265,195

7 Claims. (Cl. 108—10)

My invention relates to an interlocking roofing tile and has for its principal objects, to generally improve upon and simplify the construction of the existing forms of roofing tiles, to construct the tile with reinforcements without materially increasing the weight of the individual tile and further, to arrange the reinforcements on the tiles so that the latter are automatically spaced when assembled and laid on a roof or 10 the like.

Further objects of my invention are, to construct the tile so that when properly laid the individual tile are effectively interlocked with each other, thus minimizing the possibility of the tile 15 being blown off the roof by heavy winds, further, to construct the interlocking tile so that under certain conditions, for instance, on roofs of low pitch, the tile may be assembled to form a roof covering without the use of nails or like fastening 20 devices and which arrangement results from the interlocking of the tile when properly assembled and further, to provide interlocking tile of strong and substantial construction capable of being easily and quickly laid to form the roof covering and 25 25 the individual tile having sufficient overlap to produce maximum protection against the elements when the tile are assembled to form the covering for a roof or the like.

A further object of my invention is, to provide 30 an interlocking roofing tile of the character referred to that may be laid on the roof sheeting with either side uppermost, thus enabling two substantially different roof patterns to be produced with the same tile and without sacrificing 35 any of the desirable features and advantages of the tile, for instance, the strength thereof and also the interlocking effect that is produced throughout the entire length of the tile when assembled.

With the foregoing and other objects in view, 40 my invention consists in certain novel features of construction and arrangement of parts that will be hereinafter more fully described and claimed and illustrated in the accompanying drawing in 45 which:

Fig. 1 is a plan view of the lower left hand corner of a roof and showing a number of the tile assembled and laid thereon to form the roof covering.

Fig. 2 is a cross section taken on the line 2—2 of Fig. 1.

Fig. 3 is a cross section taken on the line 3—3 of Fig. 1.

Fig. 4 is a perspective view of one of the tile 55 and looking against the upper surface thereof.

Fig. 5 is a perspective view of one of the tile in inverted position.

Fig. 6 is a perspective view of the tile that is used at the lower left hand corner of a roof covering or the like.

Fig. 7 is a perspective view of a relatively narrow border tile that is used at the ends or the sides of the roof.

Fig. 8 is a sectional view taken on the line 8—8 of Fig. 1.

The individual tile utilized in forming the main portion of the roof covering is illustrated in Figs. 4 and 5 and said tile comprises a substantially rectangular slab 10, preferably composed of vitrified clay or earthen material and, the 15 body of said tile having a length approximately twice its width.

The side edges 11 of the tile are beveled or inclined inwardly toward their lower edges so that the width of the upper face of the tile is slightly 20 greater than the width of its under face.

Formed integral with the central portion of the tile on the under side thereof and extending the full length of the tile body is a flat reinforcing rib 12, the thickness of which is approximately 25 equal to the thickness of the tile body and thus it may be said that the longitudinal medial portion of the tile body is of double thickness with respect to the thickness of its side portions or those portions to the sides of the reinforcement. 30

The side faces 13 of the reinforcing rib 12 are beveled or inclined so that the under face of the rib is slightly wider than that portion of the rib that is joined to the tile body 10.

Formed integral with the upper surface of the 35 tile body immediately adjacent the beveled side edges 11 and extending from the butt end of the tile toward the opposite end, are narrow reinforcing ribs 14 that are substantially square or rectangular in cross section. The length of 40 these ribs is preferably somewhat less than the over-all length of the body of the tile and said ribs determine the length of longitudinal overlap 45 between the tile when the same are assembled to form a roof structure.

Formed through the upper end portion of the body 10 of the tile adjacent the corners thereof are apertures 15 and if desired, corresponding apertures 16 may be formed adjacent the upper end of the tile body through the reinforcement 12. 50 These apertures are for the reception of nails that secure the tile to the roof sheeting or other structure upon which the tile are laid.

A special tile that is used at the lower left hand corner of the roof covering is illustrated in Fig. 6 55

- and this tile has the same width and length as the tile 10. This special tile comprises a slab 17, preferably composed of vitrified clay or the like and, formed on the under side of the left hand portion of the body of this tile is a longitudinally disposed reinforcement 18, the thickness of which is substantially equal to the thickness of the body 17 of the tile so that the left hand portion of this tile has double thickness.
- 10 The longitudinal shoulder 19 between the right hand edge of the reinforcement 18 and the body 17 of the tile is beveled or inclined so that the under face of the reinforcement has slightly greater width than that portion of the reinforcement that joins the tile body 17.
- 15 Formed on the lower portion of the upper face of the slab 17 immediately adjacent both side edges thereof and extending from the butt end toward the other end are narrow reinforcing ribs 20, the length of which equals the length of the reinforcing ribs 14 on the tile 10 and, these ribs 20 are substantially square in cross section. The right hand edge 21 of the tile body 17 is inclined or beveled inwardly.
- 20 Formed through the upper portion of the tile body 17 and the reinforcement 18 are apertures 22 for the reception of nails or the like that are utilized in securing the corner tile to the sheeting or roof structure.
- 25 A tile practically identical with the corner tile 17 but with the reinforcement 18 disposed on the under side of the right hand portion of the tile body is utilized as the corner tile at the lower right hand corner of the roof covering formed by my improved tile.

30 In order that the tile forming the lowermost course or those tile immediately adjacent the eaves or lower edge of the roof structure may be laid in proper spaced relation, substantially rectangular slabs 23 of vitrified clay or the like are provided and, each of these spacing tiles has approximately the same width as the width of the tile 10 and 17 and the length of said spacing tile being slightly greater than half the length of said tile 10 and 17.

35 The side edges 24 of the spacing tile are inclined or beveled so that the upper face of each tile is slightly greater in width than the under face and when laid, these beveled faces 19 dovetail and consequently interlock with the correspondingly beveled side faces 11 of the tile 10 and the beveled side face of the reinforcing member 18 of the corner tile (see Fig. 2).

40 Formed through the upper portion of each spacing tile 23 adjacent its corners are apertures 25 for the reception of nails or like fastening devices.

45 A side border tile illustrated in Fig. 7 comprises a narrow slab 26 of vitrified clay or the like, the width of which is approximately one-third the width of the tile 10 and, formed on top of the lower portion of this border tile adjacent its side edges and extending from the butt end toward the other end are narrow reinforcing ribs 27 that are approximately square in cross section and, their length being equal to the length of the reinforcing ribs 14 and 20.

50 Where this border tile is constructed for use on the left hand end of the roof, the right hand edge 28 of the tile is inclined or beveled so that the under face of the tile body is slightly narrower than its upper face, so that said beveled face may dovetail and therefore interlock with the correspondingly beveled left hand edge 13 of the reinforcement 12 that is formed on the

5 under side of the overlying tile 10 in the next upper course. Formed through the upper portion of this narrow border tile, is one or more apertures such as 29 for the reception of a nail or like fastening device.

55 Obviously, the border tile 26 used on the right hand end of the roof necessarily have their left hand side edges beveled or inclined so as to engage the right hand beveled edge 13 on the reinforcement 12 of the overlying tile 10.

10 In laying my improved interlocking tile on a roof, a narrow eaves strip E is applied to the roof sheeting S immediately adjacent its lower edge and the corner tile 17 is now laid on the corner of the sheeting with its butt portion resting on 15 the strip E as illustrated in Fig. 8.

15 If the tile are to be anchored to the roof sheeting with nails or the like, the latter are driven through the apertures 22 into the roof sheeting and a series of alternately arranged tile 10 and 20 spacing tile 23 are now laid along the lower portion of the sheeting with the lower portions of said tile resting on the strip E.

20 The first spacing tile 23 has its left hand beveled edge 24 dovetailed against the correspondingly beveled right hand edge 19 of the reinforcement 18 on the corner tile and, the subsequent tile 10 of the lower course are disposed in spaced relation with the spacing tile 23 disposed between said tile 10 and with the beveled side 25 edges of the reinforcements 12 in dovetailed and interlocking engagement with the correspondingly inclined side edges 24 of the spacing tile.

25 As the lowermost course of tile 10 and spacing tile 23 are thus laid, they may be secured to the 30 roof sheeting by means of nails or the like, driven through the apertures 15, 16 and 25.

35 In starting the second course of tile, one of the narrow tile 26 is laid on the upper left hand portion of the corner tile 17, with the outer edges 40 of the two tile in alignment with each other and with the butt end of the narrow tile 26 bearing against the upper end of the left hand one of the reinforcing ribs 20.

45 The tile 10 forming the second course are now positioned immediately above the tile forming the first course and, said second course tile are positioned so that when moved downwardly the lower portions of the reinforcing ribs 12 will pass between and thereby dovetail and interlock with 50 the correspondingly inclined side edges 11 of the tile in the underlying course and, this movement of the second course tile is continued until the butt ends of said second course tile engage against the upper ends of the reinforcing ribs 14 55 on the tile in the lower course.

60 Thus the ribs 14 in addition to reinforcing the lower portions of the tile serve to determine the overlap between the tiles of the succeeding courses and, the engagement between the beveled side edges on the bodies of the tile and on the reinforcements 12 on the under sides of said tile, provide an interlocking arrangement that effectively maintains the tile in assembled relation and, in some instances enables the roof to be 65 laid without the necessity for nails or like fastening devices.

65 Further, the dovetailing connections between the tile and the reinforcing ribs 14 provide simple and efficient means that enables the tile to be 70 easily and quickly assembled without the requirement for measurements and the use of guide lines and thus, the work incident to the laying of the roof is facilitated and a saving of labor is effected.

75 The dovetail connections between the tile min-

imize the possibility of the tile being blown off the roof by heavy winds and, the reinforcing ribs on the lower portions of the upper faces of the tile prevent the latter from sliding lengthwise with respect to each other after being laid.

5 Inasmuch as the end portions of the wide reinforcements 12 on the under faces of the tile rest directly upon the upper end portions of the next adjacent lower course of tile and upon the 10 roof sheeting, the tile has ample strength to resist the strains resulting from substantial weights, for instance, the weight of a person walking over the tile.

The manner of reinforcing my improved tile 15 imparts to the latter certain advantages in both manufacturing, the shipping and the handling of the tile, for such reinforcement materially cuts down breakage in the handling of the tile both before and after burning and further, such 20 arrangement will aid greatly, due to the convenience of setting the tile in the kiln, as such reinforcements present straight lines in their construction so that they match and align with each other to advantage during production, firing, and handling.

When the roof covering composed of the interlocking tile has been completed, the ribs 14, 20 and 27 that extend along the margins of the ends of the roof prevent rain water running down 30 the roof from running over the edges at the ends thereof and, the exposed surfaces of the tile at the ends of the roof between the pairs of ribs 14, 27 and 20 constitute practically continuous channels that carry rain water downwardly to the 35 eaves of the roof, thus minimizing the possibility of any water overflowing the marginal ribs 14, 27 and 20.

In the foregoing description I have referred 40 to the face of the tile having the side ribs 14 as the upper or exposed face, but it is to be understood that if desired the tile may be laid on the roof sheeting with the ribs 14 resting directly upon the roof sheeting and with the centrally arranged rib 12 on the upper or exposed face of 45 the tile.

The tile when thus arranged produce a roof 50 characterized by a series of practically continuous upstanding ribs that extend from the eaves of the roof to the ridge thereof and which continuous ribs are produced by the longitudinally aligned arrangement of the ribs 12 on the individual tile.

This arrangement produces a roof of novel 55 and pleasing effect without in any way affecting the strength of the roof or the interlocking engagement between the tile that compose the roof.

In Fig. 5 the tile is shown with the rib 12 on its uppermost face.

Thus it will be seen that I have provided an in-

terlocking roofing tile that is relatively simple in construction, inexpensive of manufacture and very effective in performing the functions for which it is intended.

It will be understood that minor changes in the 5 size, form and construction of the various parts of my improved interlocking roofing tile, may be made and substituted for those herein shown and described, without departing from the spirit of my invention, the scope of which is set forth in 10 15 the appended claims.

I claim as my invention:

1. An interlocking roofing tile comprising a flat slab, a centrally arranged reinforcing rib formed 15 on the under face of said slab and extending the entire length thereof and a pair of reinforcing ribs formed on the upper face of the slab adjacent its side edges and extending from the butt end of the slab part way toward the other end.

2. An interlocking roofing tile as set forth in 20 claim 1 and the side faces of the reinforcement on the under side of the slab being beveled.

3. An interlocking roofing tile as set forth in 25 claim 1 and the side edges of which slab are beveled.

4. An interlocking roofing tile as set forth in 30 claim 1 and there being apertures formed through said slab near its upper end for the reception of fastening means.

5. An interlocking roofing tile comprising a 35 flat slab, the side edges thereof being beveled, reinforcing ribs formed on the upper surface of said slab along the side edges thereof and extending from the butt end thereof part away toward the opposite end and a centrally arranged reinforcing rib formed on the under face of the slab and extending from end to end thereof.

6. A roofing tile comprising a flat slab, reinforcing ribs formed on the upper surface of said slab along its side edges and extending from the 40 butt end of the slab part way toward the other end, the side faces of which ribs are disposed at right angles to the upper face of the slab, the side edges of the slab being beveled and a longitudinally disposed reinforcement on the 45 under face of said slab and extending the entire length thereof.

7. An interlocking roofing tile comprising a flat slab having beveled side edges, a centrally arranged reinforcing rib extending lengthwise on 50 the under side of said slab from one end thereof to the other, which reinforcement is dovetail shape in cross section and reinforcing ribs formed on the upper surface of said slab along the side edges thereof and extending from the butt end 55 of the slab part way toward the other end, the side edges of which ribs are disposed at right angles to the upper face of said slab.

RICHARD HEDRICH, SR.
